UNITED STATES PATENT OFFICE.

GEORGE A. COLMAN, OF SEATTLE, WASHINGTON.

TIMBER-PERFORATING MECHANISM.

Application filed December 21, 1922. Serial No. 603,242.

My invention relates to the art of timber perforating mechanism. More particularly my invention relates to providing a mechanism which will efficiently and quickly provide with perforations a pole to be treated with a preserving compound.

It is becoming the practice to very thoroughly impregnate that portion of poles such as for example, as are used for telegraph or piling purposes, which extends for about one foot above the ground and which extends two feet beneath the ground. The cellular structure of wood poles is such that the transverse ducts are few or of a character which causes the wood to resist impregnation by a preserving compound, while the longitudinal ducts of the pole more freely permit of the passage of the impregnating fluid.

Therefore, by perforating the outer portion of the section indicated, the difficulty as respects the transverse ducts is overcome. The perforations make available the longitudinally disposed ducts in the pole so that the impregnating fluid under pressure may readily move throughout the desired portion to be treated.

It is well known that if recourse be had to high temperature in the treating retorts in order that a thorough impregnation of the wood product may be insured, a most serious impairment of the strength and durability of the wood product is incurred. Hence, high temperature during the treatment process must positively be avoided. Moreover, it has been demonstrated that refractoriness of many wood structures prevents satisfactory impregnation even when high temperatures are employed. Therefore, experience teaches that a proper perforating of that portion to be treated seems to present the solution of the difficulty above set forth. To secure a uniformity of treatment and insure certainly that there will be no part which is not thoroughly impregnated, the perforations must be regularly disposed over such portion of the pole surfaces as may require treatment. Serious objections obtain to employing a positively driven drum when the same is applied to poles which present an undressed surface and therefore an uneven surface. Also, such mechanism tends to tear the wood fiber. Moreover, manifestly the cost of the process of perforating must be limited by the advantage which it contributes to the treatment of the pole. Therefore, any per-

forating mechanism, to be commercially useful, must be capable not only of efficiently and scientifically performing its perforating function, but it must be capable of performing its duty economically. The weight of heavy timbers, the tapering character of poles and the unevenness of surface presented by poles render difficult the supplying of the perforations with a uniformity of depth by any drum process. In treating a dressed product, there is no problem of adjusting the same for the perforating operation and hence the drum process may satisfactorily serve the purpose in that case but as explained is not adapted to handle poles of dimension which are not uniformly rectangular.

Furthermore, the importance of treating the pole throughout its entire length is becoming more and more recognized. The perforating means, therefore, should be adapted to supply the pole for its entire length with perforations, as well as any given portion intermediate its length.

In general, the objects of my invention are to overcome the difficulties above set forth. A primary object of my invention is to provide a machine which will perforate the desired portion of a pole either throughout its entire length or a part thereof at the end or intermediate the ends, uniformly as to depth of perforations and uniformly as to spacing. Another primary object is to provide such a mechanism which will perforate poles economically and efficiently. A primary object is to provide a perforating mechanism which will automatically center the pole so that the mounting or supporting of the pole itself will tend to result in uniformity of depth of perforations and uniformity as to spacings.

A further object of my invention is to provide a perforating mechanism which depends for its actuation to provide spacing for the perforations in the line of the advancing tool upon the rotary movement of the timber being operated upon. Also it is a primary object to provide a form of perforating tooth which will not objectionably tear the wood fiber.

The above mentioned general objects of my invention, together with others inherent in the same, are attained by the mechanism illustrated in the following drawings, the same being merely preferred exemplary forms of embodiment of my invention, throughout which drawings like reference numerals indicate like parts.

Figure 1 is a side view in elevation of a mechanism embodying my invention;

Fig. 2 is a plan view of the same;

Fig. 3 is an end view of the chuck member;

Fig. 4 is a view in longitudinal section of said chuck and the associated actuating mechanism for said chuck;

Fig. 5 is a view in part elevation and section of the perforating mechanism;

Figs. 6 and 7 are views of details of said perforating mechanism, showing the form of the perforating teeth;

Fig. 8 is a view illustrating the pole discharging arm;

Fig. 9 is a plan view of the driving mechanism of my invention;

Fig. 10 is a view in longitudinal section of a modified form of perforating means; and

Fig. 11 is a view of a modified form of my invention having a steel frame and a plurality of perforating means.

Upon the base frame 12 a vertical frame 13 is disposed which vertical frame 13 supports the overhanging frame 14.

The base frame 12 is provided with two bunks 15 and 16 on which a pole 17 may be temporarily brought to rest while being positioned in the machine. On one end portion of said base frame, spaced rollers 18 are mounted to form a rotary support for one end portion of the pole 17. These spaced rollers 18 are preferably movably mounted. On the other end portion of said base frame 30 is mounted on shaft 19 a chuck 20. Intermediate said spaced rollers and said chuck are preferably disposed the two eccentrics 21, which have bevelled gears 22 which mesh with pinions 23 mounted on shaft 24. On 35 a shaft 25 are mounted arms 26 which function to discharge the pole being treated from the mechanism herein set forth.

A chuck 20 is preferably provided with three radially equidistant disposed slots 27, in which slots are disposed radially movable dogs 28, 29 and 30, two of which may be 45 preferably provided with spikes 31, while the third may be preferably provided with a shoe 32 whereon the end of the piling may 50 rest after it is first moved against the chuck and before it is securely clamped therein.

The dogs, 28, 29 and 30 have rack teeth 33 on their rear sides, each of which mesh with pinions 34, said pinions in turn meshing with pinions 35 and these mesh with rack bars 36. These bars are rigid with a disc 37 which abuts against a nut 38 and said disk 37 is provided with flanges 39 which hook loosely over a flange 40 on the 55 end of the nut 38. This nut 38 is threadedly mounted upon shaft 19 and has keyed thereto a friction pulley 41 by key 42. This said pulley is operatively disposed to engage with a friction driving pulley 43 on shaft 44.

60 Between the overhanging frame members

14 is disposed a perforating mechanism preferably consisting of a compressed fluid cylinder 45 mounted on a base member 46. This base member is slidably disposed on trackways 47 extending lengthwise of the 70 upper members of the overhanging frame. Between the lower members of the overhanging frame 14 is a perforating disk 48 mounted in a sliding member 49, the same being vertically and also longitudinally 75 slidably movable between said members. The sliding member 49 is carried by piston rod 50 which is connected to piston 51, operatively disposed in cylinder 45.

Two compressed air tanks 52 and 53 are 80 mounted on the overhanging frame 14. The tank 53 is arranged to receive compressed air from the tank 52 through pipe connections 54 and 55. Tank 53 is also connected by a flexible connector 56 to the upper part 85 of cylinder 45 so that a substantial air pressure may be maintained continuously in the upper end of the pneumatic cylinder whereby a substantially uniform pressure may be exerted upon the piston 51. The tank 52 is connected by means of the pipe 57 and the flexible connector 58 to the lower end of the cylinder 45.

A regulating valve 59 in pipe 55 maintains the pressure in tank 53 at a predetermined 90 magnitude lower than that in tank 52. A three-way valve 60 of any well known design in pipe 57 serves to establish communication between said lower part of cylinder 45 and the exhaust outlet 61 of pipe 62. Thus, to lift the perforating means 48, the valve 60 is turned to admit the relatively higher pressure of tank 52 to the lower part of cylinder 45, said tank 52 pressure being higher than that in 53, the piston 51 is forced 95 upward against the pressure of tank 53. To lower the piston 51 and its perforating means 48, the valve 60 is turned to exhausting position so that the pressure in the lower part of the cylinder 45 is dissipated into the 100 atmosphere.

The driving mechanism includes a motor 63 connected by pinion 64 and gear wheel 65 with shaft 66. The main shaft 19 is driven from shaft 66 by means of sprocket wheel 67, sprocket chain 68, sprocket wheel 69, idler shaft 70, sprocket wheel 71, sprocket chain 72 and sprocket wheel 73. Sprocket wheel 67 is controlled by clutch 74 which is operated by a lever 75 and handle 76. A 112 feed screw 77 is in threaded connection with the base member 46 and said feed screw is actuated from shaft 19 by sprocket wheels 78 and 79 and sprocket chain 80. Shaft 24 is driven by sprocket 81, sprocket chain 82 and sprocket wheel 83 on shaft 66. Clutch 84, movable by lever 85 is used for connecting and disconnecting sprocket wheel 83 and shaft 66. Shaft 25, on which are disposed arms 26 for discharging the pole, is driven 118

from shaft 19 by sprocket wheels 86 and 87 and sprocket chain 88. Clutch 89 and lever 90 serve to connect and disconnect shaft 25 and sprocket wheel 87. Friction wheel 43 on shaft 44 is driven by sprocket wheel 93, sprocket chain 94 and sprocket 95, clutch 96 and lever 97 serving to connect and disconnect shaft 66 with sprocket 95. Friction wheel 91 may be moved into or out of contact with pulley 41 by lever 98 and link 99.

In the driving diagram in Fig. 9, some of the parts are moved out of their normal position to facilitate illustration, the same serving to set forth merely one form of driving means. My invention is indifferent as to the particular form of such means except as herein indicated otherwise.

In the form of perforating means, illustrated in Fig. 10, a compressed fluid cylinder 100 is provided with a piston 101 having a pressure face 102 on its lower side having a pressure area with a diameter equal to that of the cylinder, and having a pressure face 103 on its upper side relatively smaller than 102. The core wall 104 limits the pressure face 103 to an annular ring form, so that a constant source of pressure may serve both to lift said piston and yieldingly maintain the same in a depressed position. The cylinder 100 has mounting 105 by which it is longitudinally slidably supported between channels 106 and 107. The disk mounting member 108 is vertically slidably mounted in mounting 105 on guides 109. Gripping means 110 in the form of a split nut of well known design may be used to releasably engage the feed screw 111 so that said cylinders may be located selectively on said feed screws. Conduits 112 and 113 serve to admit fluid pressure to pressure faces 102 and 103 respectively. Flexible conduits 114 and 115 connect conduits 112 and 113 respectively to a three-way valve 116, whereby the fluid pressure may be admitted to the pressure face 102 and exhausted therefrom as desired.

In the modified form, Fig. 11, two cylinders 100 and 117 of the preferred form are shown mounted on a feed screw 111. Pipe 118 connects valve 116 to tank 119, which serves as a common relatively constant source of fluid pressure for both the pressure faces of each of the pistons in cylinders 100 and 117. Flexible connectors 120 and 121 connect cylinder 117 to the connections 122 and 123 of the flexible connectors 114 and 115, said connections operating similarly to that described for cylinder 100. Having two such perforating means operating simultaneously, it is manifest that the time for completing a given perforating operation is divided in two.

The disk 48 is preferably provided with demountable teeth 124. These are preferably provided between disks 125, 126 and 127. These may be arranged in single rows

in the perforating disk or three such disks may be employed as shown in Fig. 7 and two rows of said perforating teeth provided. These teeth are preferably provided with a relatively short conical point 128. Above 70 the point the walls of the tooth may be concave at 129. The heads 130 serve to anchor the teeth in the disks 125, 126 and 127 when these disks are clamped tightly together by means of bolts 131. 75

The mode of operation of a perforating device embodying my invention is as follows: A pole 17 is brought to the perforating machine by any well-known suitable feed mechanism such as an overhead crane or chain belt. At first it is placed on the bunk 15 or on bunk 16 and rollers 18. The eccentrics 21 serve to lift and move the pole to the chuck 20. Thereupon, the pulley 43 is caused to engage the pulley 41 which imparts a rotary movement to the nut 38 through the key 42. Since the nut 38 is threadedly mounted upon shaft 19, the rotary movement causes it to move lengthwise of said shaft. When this movement is such as to cause the nut to advance towards the chuck, the nut carries with it the disc 37 which is idly mounted on the nut 38 so that there is no relative movement as respects chuck 20 and disk 37. The longitudinal movement imparted to disk 37 in turn moves the racks 36 integrally from one disc 37 across the pinions 35, causing the same to rotate and this in turn imparts its rotary movement to pinion 34, which engages rack 33, on the base of each dog, causing the same to move towards the center of the chuck in slots 27. That is, each of the dogs 28, 29 and 30, carried by the racks 33, are caused to move simultaneously and uniformly towards the center of the chuck. Thus automatically, the pole is practically centered as respects the chuck. The opposite end is rotatably supported on rollers 18. 100

When the pole is thus adjusted in position, the chuck 20 is caused to rotate so that the rotary movement is imparted to the pole 17. Thereupon, compressed air is exhausted from the lower part of cylinder 45, which results in the forcing downward of piston 51 and this in turn forces the disk 48 down upon the rotating pole 17, causing the teeth to perforate the pole causing the faces 132 of the disks 125, 126 and 127 to ride upon the pole. Since the pole is rotating it will cause the disk 48 to rotate. As disk 48 rotates, the screw thread 77 also is caused to rotate at a pre-determined rate so that the disk 48 is caused to travel in the helical path about the pole. Any unevenness in the pole is compensated for by the raising of the piston against the compressed air in the cylinder 45; that is, the disk 48 is yieldingly held against the pole. The cylinder 45 is caused to move lengthwise of the device sliding on tracks 110 115 120 125 130

47 engaging the base member 46. The lateral displacement of the disk 48 is prevented by the lower members of the overhanging frame 14.

5 The teeth are preferably of the form illustrated since experience has taught that said form avoids injuriously tearing the wood fiber. The form of the tooth as indicated insures a clean-cut perforation. When the 10 perforating operation has been completed, as respects that portion of the pole to be perforated, the actuating mechanism connected with shaft 19 is disconnected by means of clutch 74 and since the feed screw 77 is 15 actuated by means connected with shaft 19, the stopping of shaft 19 obviously simultaneously stops the feed screw 77. Thereupon, compressed fluid is admitted to the lower side of the piston 51 and the perforating disk 20 48 is raised as respects the pole. The dogs 28, 29 and 30 are caused to release their grip upon the pole 17 and the eccentrics 21 are caused to engage the pole and move it clear of the chuck 20. Thereupon, the disengaging arms 26 are caused to throw the pole to one side which occurs when the arms 26 are caused to assume the position indicated in 25 dotted line in Fig. 8.

30 The modified form in general operates in a manner similar to that above described. Obviously the time required for completing the perforating of a given portion of a pole, or the entire pole, is made just one-half by having two perforating means working 35 simultaneously as indicated in Fig. 11. A number of said perforating means in excess of two, all similar in construction and connections to those described, obviously would reduce the time required to complete the 40 perforating operation and preferably would be provided when the entire pole is to be perforated. The disks are preferably operated by the same feed screw 111 and these perforating cylinders are preferably 45 releasably connected to said feed screw 111 so that they can be adjusted to any desired position thereon in order to cause each perforating disc to perform one-half of the 50 operation.

55 Obviously, changes may be made in the forms, dimensions, and arrangement of the parts of my invention, without departing from the principle thereof, the above setting forth only preferred forms of embodiment.

55 I claim:

60 1. A pole perforating mechanism embodying a pole adjusting and supporting mechanism whereby a pole may be rotated while supported; and a perforating means yieldingly pressed against said pole, which means is automatically movable lengthwise of said pole as the latter rotates and is caused by contacting said pole to move relatively over said pole circumferentially in synchronism 65 with the rotation of said pole.

2. A pole perforating mechanism embodying a base frame; spaced rollers mounted on one end portion of said frame, whereby one end portion of said pole may be rotatably supported; a chuck disposed at the other 70 end of said base frame; means mounted on said base frame intermediate said rollers and said chuck, whereby a pole may be moved up and down and longitudinally of the frame and adjustably held against said 75 chuck; a vertical frame on the chuck end portion of the base frame; an overhanging frame mounted on said vertical frame; a perforating means slidably mounted on said overhanging frame, said means being caused 80 by contacting said pole to move relatively over said pole circumferentially in synchronism with the rotation of said pole, and suitable actuating means for said chuck and 85 perforating means.

3. A pole perforating mechanism embodying a base frame; spaced rollers mounted on one end portion of said base frame, whereby one end portion of said pole may be rotatably supported; a chuck disposed at 90 the other end of said base frame; means mounted on said base frame intermediate said rollers and said chuck, whereby said pole may be moved up and down and longitudinally of the frame and adjustably held against said chuck; a vertical frame on the chuck end portion of said base frame; an overhanging frame supported by said vertical frame; a perforating means slidably mounted on said overhanging frame, said means being caused by contacting said pole to move relatively over said pole circumferentially in synchronism with the rotation of said pole, pressure means whereby said 95 perforating means may be caused to yieldingly press upon the pole; a feed screw for said means, whereby the movement lengthwise of the overhanging frame of said perforating means may be regulated; and suitable actuating means for said chuck and 100 perforating means.

4. A pole perforating mechanism embodying a base frame; spaced rollers mounted on one end portion of said base frame, whereby one end portion of a pole may be rotatably supported; a chuck disposed at the other end of said base frame, whereby said pole may be adjustably held and rotated; grooved eccentric means mounted on said base frame intermediate said rollers and said chuck, whereby said pole may be moved up and down and longitudinally of the frame and adjustably held against said chuck; a vertical frame on the chuck end portion of said base frame; an overhanging frame mounted on said vertical frame; a perforating tooth disk slidably mounted on said overhanging frame and vertically adjustable; pressure means whereby said perforating disk may be caused to yieldingly press 110 115 120 125 130

upon said pole with a uniform pressure and the rotary movement of said pole may be caused to actuate said disk; and a feed screw whereby the perforating disk may be actuated lengthwise of the overhanging frame.

5. In a pole perforating mechanism, the combination of means to support and rotate said pole on its longitudinal axis, said axis being fixedly held; means to perforate the same; and means to cause an automatic relative movement between said perforating means and the pole lengthwise of the pole as it rotates, whereby the perforations form a spiral around the pole, and whereby said 10 perforating is one continuous operation throughout the section to be perforated.

6. A pole perforating mechanism embodying a pole adjusting and supporting mechanism, whereby a pole may be automatically centered and rotated while supported on its longitudinal axis, said axis being fixedly held; a plurality of perforating means operatively disposed with respect to said mechanism, said means being caused by contacting said pole to move relatively over said pole circumferentially in synchronism with the rotation of said pole, whereby a series of perforations may be made in said pole simultaneously; and actuating means whereby said perforating means may be caused to automatically move lengthwise of said mechanism.

7. A pole perforating mechanism embodying a pole adjusting and supporting mechanism, whereby a pole may be automatically centered and rotated while supported on its longitudinal axis, said axis being fixedly

held; a plurality of perforating means operatively disposed with respect to said mechanism, said means being caused by contacting said pole to move relatively over said pole circumferentially in synchronism with the rotation of said pole, whereby a series of perforations may be made in said pole; actuating means whereby said perforating means may be caused to automatically move lengthwise of said mechanism; and means whereby said perforating means may be selectively disposed upon said actuating means.

8. In a pole perforating mechanism, the combination of means to support and rotate said pole; means to perforate the same, said means including a wheel with teeth which engage the pole; and means to cause an automatic relative movement between said perforating means and the pole lengthwise of the pole as it rotates, whereby the perforations form a spiral around the pole, and whereby said perforating is one continuous operation throughout the section to be perforated.

9. In a pole perforating mechanism, the combination of means to rotate said pole; and a perforating means disposed to be yieldingly held against said pole, said means including a disk with teeth and said teeth being caused by contacting said pole to move relatively over said pole circumferentially in synchronism with the rotation of said pole.

In witness whereof, I hereunto subscribe my name this 14th day of December, A. D. 1922.

GEORGE A. COLMAN.
